CUP RACK

John W. Weisner, Highland Springs, Va.

Application February 24, 1950, Serial No. 145,927

3 Claims. (Cl. 211—71)

1

This invention relates to dish washing machines, and more particularly to an electrically controlled automatic dish washing machine.

A main object of the invention is to provide a novel and improved automatic dish washing machine which is very simple in construction, which is automatic in operation, and which may be employed in locations where a hot water supply pipe line is not available.

A further object of the invention is to provide an improved automatic dish washing machine which involves relatively few parts, which is inexpensive to manufacture, which is sturdy in construction, which includes improved rack means for supporting the various dishes and utensils to be washed, and which is provided with automatic electrical cycling means for controlling the intake and exhaust of water during a dish washing cycle.

Further objects and advantages of the invention will become apparent from the following description and claims, and from the accompanying drawings, wherein:

Figure 1 is a side elevational view of an improved automatic dish washing machine constructed in accordance with the present invention;

Figure 2 is a top plan view of the machine of Figure 1, with the top cover removed;

Figure 3 is a view similar to Figure 2 with the dish and utensil supporting rack elements removed;

Figure 4 is a vertical cross-sectional view of the machine taken on line 4—4 of Figure 1;

Figure 5 is a horizontal cross-sectional view taken on line 5—5 of Figure 4;

Figure 6 is a perspective enlarged detail view of a flatware supporting rack employed in the machine of Figure 1;

Figure 7 is a detail cross-sectional view taken on line 7—7 of Figure 4;

Figure 8 is an enlarged perspective detail view of the cup supporting rack employed in the machine of Figure 1;

Figure 9 is a side elevational view of a portion of the lower dish supporting element of the machine and showing a dish supported in a supporting bracket attached to the lower supporting element of the machine;

Figure 10 is a plan view of the dish supporting rack structure shown in Figure 9;

Figure 11 is a perspective view of the utensil supporting rack employed in the machine of Figure 1;

2

Figure 12 is a schematic wiring diagram showing the electrical connections of the machine;

Figure 13 is an enlarged side elevational detail view of the automatic stop switch employed to de-energize the driving motor of the machine at the end of a dish washing cycle.

Figure 14 is an end elevational view of the cup supporting rack of Figure 8, but with the cup in position thereon.

Referring to the drawings, 11 designates a generally cylindrical, vertical housing having a bottom wall 12 and formed with an interior, upwardly concave partition wall 13 defining a dish washing chamber 14 in the upper portion of housing 11. Partition wall 13 has a depressed central portion 15 in which is secured a vertical bearing sleeve 16. Rotatably and sealingly positioned in said sleeve is a vertical shaft 17, said shaft having secured to its top end the agitating vanes 18, 18'. Vanes 18, 18' may be of any suitable shape and are suitably inclined so as to scoop water and propel the water upwardly when shaft 17 is rotated. The lower end of shaft 17 is suitably journaled to the bottom wall 12 and carries a bevel gear 19. Designated at 20 is an electric motor. A bevel gear 21 is secured on one end of the shaft of said motor, said bevel gear 21 being in mesh with the bevel gear 19, whereby shaft 17 is drivingly connected to the motor shaft. The other end of the motor shaft carries a pulley 22. Designated at 23 is a discharge pump. The driving shaft 24 of said pump carries a pulley 25 which is coupled to pulley 22 by a belt 26. The intake passage of pump 23 is connected by a flexible conduit 27 to a discharge elbow fitting 28 connected to the lower end of the depressed wall portion 15. Elbow fitting 28 includes a normally closed valve 29 which is operated by a solenoid 30, valve 29 being opened when solenoid 30 is energized. The outlet passage of pump 23 has a discharge conduit 31 connected thereto.

Secured to one side of housing 11 is a water reservoir 32, said reservoir being suitably insulated against the escape of heat by an insulating jacket 33, and being provided with a removable top cover 34. Secured in the lower portion of reservoir 32 is a conventional electrical heating element 35, said element being provided with a suitable thermostatic switch to regulate the temperature of the water in reservoir 32. The wall between chamber 14 and reservoir 32 is formed with an opening in which is seated the disc 36 of a valve, whose stem is connected to the plunger of a solenoid 31, the disc 36 being nor-

mally biased to closed position and being moved to open position when solenoid 37 is energized.

The lower portion of reservoir 32 comprises a housing 38 in which is mounted a control apparatus for regulating the time of operation of the motor 20 and the energization of the valve solenoids 30 and 37. Designated at 39 is a shaft journaled in a bracket 40 secured to bottom wall 12, said shaft carrying a bevel gear 41 which is in mesh with bevel gear 19. Secured to shaft 39 is a flexible shaft 42 which extends into housing 38 and is connected to the input shaft of a speed reducing unit 43 mounted in said housing. The output shaft of unit 43 carries a worm 44 which is in mesh with a worm gear 45 carried on a vertical shaft 46 journaled in housing 38. Mounted in said housing concentrically with shaft 46, as shown in Figure 12, is a flat conductor ring 47. Designated at 48, 49 and 50 are the segments of an outer, upstanding ring, the ends of said segments being insulated from each other by short insulating spacers 51.

As shown in Figure 12, a radial arm 52 is secured to shaft 46, said arm being of insulating material and having secured thereto a conductive extension 53, said extension being provided with a resilient conductive tip 54 which engages the upstanding ring segments 50, 49 and 48 successively as the arm 52 rotates counterclockwise, as viewed in Figure 12. Secured to extension 53 is a conductive brush 55 which continuously engages the flat ring 47. Designated at 56 and 57 are the respective power supply wires. Connected to supply wire 56 is a wire 58 which is connected to one terminal of the motor 20. The wire 56 is connected to the ring 47. The other terminal of the motor 20 is connected to supply wire 57 by a wire 59 which includes a normally open push button switch 60. Connected in parallel with switch 60 is a normally closed switch 61. Switch 61 comprises an upstanding bracket 62 located adjacent the gap between segments 48 and 50 and carrying a block 63 of insulating material. Secured to the upper portion of block 63 is a depending spring arm 64 which normally engages a contact 65 secured to the lower portion of block 63. A wire 66 connects spring arm 64 to wire 59 on one side of switch 60. A wire 67 connects a terminal 68 on switch 61 to wire 59 on the other side of switch 60. Terminal 68 is connected internally of block 63 to the contact 65. The lower end of spring arm 64 is located in the path of movement of an insulating sleeve 69 carried in extension 53. The sleeve 69 is arranged to engage spring arm 64 and flex arm 64 outwardly, as shown in dotted view in Figure 13, thereby opening the motor supply wire 59 at the end of a cycle of operations. When the arm 52 is caused to rotate further, as by manually closing switch 60 to thereby energize the motor, the sleeve 69 slips past the lower end of spring arm 64, allowing said spring arm to return into engagement with contact 65.

As shown in Figure 12, one terminal of each of the solenoids 30 and 37 is connected to line wire 57. The other terminal of solenoid 37 is connected by a wire 70 to the ring segment 49. The other terminal of solenoid 30 is connected by respective wires 71 and 72 to the respective ring segments 48 and 50.

It will be seen from Figure 12 that the spring arm 64 is located inwardly adjacent the spacing insulator 51 between the ends of the segments 48 and 50. At the end of a cycle of operations, the tip 54 will therefore engage said insulator 51 and neither of the solenoids 30 and 37 will be ener-

gized. The motor supply circuit will also be open since spring arm 64 will be flexed away from contact 65. This represents the starting position of the machine.

To place the machine in operation, a supply of lukewarm water is first placed in the dish washing chamber 14 and in the water reservoir 32. The heater 35 is energized by closing the switch which controls its electrical circuit. Switch 60 is then closed, energizing the motor 20 through a circuit comprising line wire 57, wire 59, switch 60, the motor winding, wire 58 and line wire 56. Sleeve 69 slips past spring arm 64, allowing said spring arm to engage contact 65, thereby shunting switch 60. Switch 60 may then be released, the motor remaining energized by the closure of switch 61. Solenoid 30 becomes energized by a circuit comprising line wire 56, ring 47, conductor 53, tip 54, segment 50, wire 72, wire 71, the solenoid winding, and wire 57. The drain valve 29 is thus opened, and the lukewarm water gradually drains from the dish washing chamber during the first phase of operation of the agitating blades. Valve 29 closes when tip 54 leaves segment 50 and engages segment 49. This energizes solenoid 37 through a circuit comprising line wire 57, the solenoid winding, wire 70, segment 49, tip 54, conductor 53, ring 47 and line wire 56. The energization of solenoid 37 opens the hot water valve disc 36, admitting hot water into the chamber 14 during the second phase of operation of the agitating blades. Valve disc 36 closes when tip 54 leaves segment 49, de-energizing solenoid 37, and engages segment 48. Solenoid 30 again becomes energized through a circuit comprising line wire 56, ring 47, conductor 53, tip 54, segment 48, wire 71, the solenoid winding, and line wire 57. This opens valve 29, allowing the rinse water to drain during the third phase of operation of the agitator blades. As sleeve 69 engages spring arm 64, the motor circuit is opened at contact 65 and the tip 54 stops in engagement with the insulating spacer 51 between segments 48 and 50, whereby the solenoid 30 becomes de-energized and the cycle of operation is completed.

During the initial phase of the cycle, when lukewarm water is present in chamber 14, the agitator blades 18, 18' splash water upwardly in a vigorous manner, and cause the dishes and utensils in the upper portion of the chamber to be cleansed of dirt. During the second phase of the cycle, the hot rinse water is admitted into the chamber 14. During the third and final phase of the cycle, the valve 29 is opened to drain the rinse water from the chamber 14, allowing the agitator blades to splash the clean water upwardly to thoroughly rinse the dishes and utensils during this period.

The cycle may be repeated one or more times by merely momentarily closing the push button switch 60 at the end of each cycle.

It will be noted that any rinse water remaining from a preceding cycle may be used for the initial phase of a succeeding cycle. This provides efficient utilization of the water and minimizes the necessity of replenishing water in reservoir 32.

The drain solenoid 30 may be energized independently to drain the final remaining rinse water, if so desired, by means of a manually operated switch 73 connected between line wire 56 and wire 71.

Referring now to Figure 3, it will be seen that the blades 18 and 18' are mounted on a transverse supporting rod 74 secured to the top end of

5

shaft 17. Blades 18 extend substantially radially with respect to the vertical shaft 17, as shown in Figure 4, and are formed with the upwardly inclined side flanges 75. Blades 18' are in side-by-side relation with respect to blades 18 and are formed with the upstanding inner marginal flanges 76 and have upwardly inclined, outer side flanges 77. The blades 18' are larger in width than the blades 18, and the flanges 77 diverge outwardly with respect to the adjacent blades 18. Said blades 18' are inclined with respect to the horizontal, as shown in Figure 4.

The housing 11 is provided at its intermediate portion with a plurality of inwardly projecting lugs 78 on which is supported the partition or circular wire grille 79, said grille having a peripheral circular frame 80 fabricated from metal tubing. Designated at 81 is an auxiliary or rectangular grille provided with depending legs 82 which are secured to the grille 79 at one side thereof, as shown in Figure 4. The grille 81 is adapted to support pieces of flatware in vertical positions, as shown in Figure 4, said pieces being inserted in the meshes of the grille. Secured to the grille 79 are a plurality of cup racks 83, shown in detail in Figure 8. Each cup rack 83 comprises a rectangular wire frame 84 to the sides of which are secured spaced rearwardly, offset, longitudinal bars 85, 86. Secured to the ends of the upper bar 86 are inclined struts 87, 87 supporting frame 84 in an inclined position. Secured to the bottom longitudinal element 88 of frame 84 are spaced, upstanding rods 89. Secured to the top end of each rod 89 is a cross bar 91 having upturned ends 92, 92. Adjustably or movably secured to the upper portions of the side elements of frame 84 are sleeves 93, 93 carrying the top arm 94 of the frame and carrying an additional top arm 95 forwardly offset from arm 94. As shown in Figure 8, each sleeve 93 is adjustably secured in a select position of its movement to the adjacent side element of the frame 84 by means of a set screw 93a. The cups are supported in inverted positions on the cross bars 91 with the bottom edges of the cups abutting the top arms 94 and 95. As shown in Figure 14, a cup C has its top edge supported on the cross arm 91 and has its bottom edge contacted by the arm 95 with the side of the cup contacted by the arm 94.

Secured concentrically on grille 79 is an arcuate bar member 96 to which are secured a plurality of outwardly extending dish racks 97. Each dish rack 97 comprises an arcuately bent, inwardly offset, U-shaped wire loop 98, as shown in Figures 9 and 10, the arms of loop 98 being connected by spaced U-shaped, small loops 99, whereby a dish 100 may be supported in an upstanding position in the manner clearly shown in Figure 9. As further shown in Figure 4, the dishes are supported in substantially vertical, radial planes around the vertical axis of housing 11.

Designated at 101 is a circular shelf or top grille employed for supporting utensils in the upper portion of the housing 11. Secured to the periphery of grille 101 are a plurality of depending legs 102 having inwardly offset bottom ends 103 engaging over the circular frame 80 of the lower grille 79 in the manner shown in Figure 4, whereby the top grille 101 is detachably supported in housing 11 over the lower grille 79.

The housing 11 is provided with a removable top cover 104, providing access to the interior of the upper chamber 14 of said housing.

6

While a specific embodiment of an improved automatic dish washing machine has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a dish washing machine, a rack adapted to be fixedly positioned upon a supporting grille and comprising an upstanding frame including a longitudinal bottom element and spaced side elements rising from said bottom element, a plurality of upstanding rods arranged in longitudinal spaced relation along and spaced from one side of said frame and each having the lower end fixed to the bottom element of said frame, a cross arm fixed on the upper end of each of said rods, at least a pair of spaced longitudinally extending arms cooperating with said cross arms for supporting cups in inverted positions and connected to the side elements of said frame for movement toward and away from said cross arms, and means for holding said pair of arms in any select position of their movement.

2. In a dish washing machine, a rack adapted to be fixedly positioned upon a supporting grille and comprising an upstanding frame including a longitudinal bottom element and spaced side elements rising from said bottom element, a plurality of upstanding rods arranged in longitudinal spaced relation along and spaced from one side of said frame and each having the lower end fixed to the bottom element of said frame, a cross arm fixed on the upper end of each of said rods, at least a pair of spaced longitudinally extending arms cooperating with said cross arm for supporting cups in inverted positions and connected to the side elements of said frame for movement toward and away from said cross arms, and means for holding said pair of arms in any select position of their movement.

3. In a dish washing machine, a rack adapted to be fixedly positioned upon a supporting grille and comprising an upstanding frame including a longitudinal bottom element and spaced side elements rising from said bottom element, a plurality of upstanding rods arranged in longitudinal spaced relation along and spaced from one side of said frame and each having the lower end fixed to the bottom element of said frame, a cross arm fixed on the upper end of each of said rods, at least a pair of spaced longitudinally extending arms cooperating with said cross arms for supporting cups in inverted positions, a bar extending between the side elements of said frame above and spaced from the bottom element of said frame and fixed to the side elements of said frame, and upstanding struts each having the upper end secured to said bar and having the lower end adapted to rest upon the supporting grille.

4. In a dish washing machine, a rack adapted to be fixedly positioned upon a supporting grille and comprising an upstanding frame including a longitudinal bottom element and spaced side elements rising from said bottom element, a plurality of upstanding rods arranged in longitudinal spaced relation along and spaced from one side of said frame and each having the lower end fixed to the bottom element of said frame, a cross arm fixed on the upper end of each of said rods, at least a pair of spaced longitudinally extending arms cooperating with said cross arms for supporting cups in inverted positions, a sleeve carried by each of the adjacent ends of said pair of arms and slidably receiving the upper end portion of the adjacent frame side element, and a securing element carried by each sleeve and engageable with the adjacent frame side element for holding said pair of arms in any select position of their movement.

JOHN W. WEISNER.
